UNITED STATES PATENT OFFICE.

GRAFTON D. DORSEY, OF NEW YORK, N. Y.

PROCESS OF PRODUCING METAL PIPE.

No. 909,376.

Specification of Letters Patent. Patented Jan. 12, 1909.

Application filed March 28, 1908. Serial No. 423,810.

To all whom it may concern:

Be it known that I, GRAFTON D. DORSEY, a citizen of the United States, and resident of New York city, in the county of New York and State of New York, have invented a new and useful Improvement in Processes of Producing Metal Pipe, of which the following is a specification.

My invention relates to a process of producing metal pipe, particularly soft metal pipe such as antimonial lead pipe which is provided at frequent intervals with an identifying mark such as a trademark, size mark or any distinguishing character formed in the metal of the pipe itself.

Lead pipe has heretofore been hand marked after completion. The cost of hand marking is such that the marks are usually only stamped once on a length of pipe. Moreover, when pipe is coiled as it comes from the press, it is impracticable to thereafter apply the mark or marks at frequent intervals throughout its length.

My invention, therefore, consists in a method of applying the desired marks to the pipe at frequent intervals throughout its length in the process of manufacture.

The accompanying drawing illustrates mechanism which may be employed in carrying out my process.

Figure 1 is an elevation of so much of a press with my invention applied to it as is necessary to clearly understand the same. Fig. 2 is a side elevation of Fig. 1. Fig. 3 is a detail edge view of a marking pulley or roll. Fig. 4 is a length of completed pipe showing the identifying mark thereon. Fig. 5 is a view similar to Fig. 1, of a modified form of apparatus for carrying out the invention.

Reference numeral 1 designates the head of any suitable press for forming pipe such as lead pipe or antimonial lead pipe by extrusion. Molten metal is supplied to the press in any approved manner. The pipe 2 is shown issuing from the press warm and not fully hardened. The pipe, which in the present instance is to be coiled, passes over the marking pulley 3. The pulley is provided at one or more points on its face engaging the pipe with the desired identifying marks 4, arranged reversely, as for printing. The pulley 3 may be mounted on a shaft 4 and the

shaft may be impelled by drive pulleys 5 at the proper speed to suit the rate of progress of the pipe over pulley 3. In other cases the pull of the completed pipe is sufficient to rotate the marking pulley. As the warm and relatively soft pipe passes over pulley 3 the identifying marks are impressed upon the pipe by virtue of its own weight. In the structure shown in Figs. 1 and 2, the pipe 2 as it passes from the marking pulley is to be coiled or wound on a spool for the market.

Fig. 4 shows a completed length of pipe bearing the identifying mark 4^a at frequent intervals throughout its length.

In Fig. 5 is shown a press similar to that of Figs. 1 and 2, in connection with which are employed two marking rolls 3, 3^a. Either one or both of these rolls may carry characters to be impressed upon the pipe. The rolls may originally be set at a certain distance apart calculated for a particular size of pipe so that the mere passage of the pipe between them serves to impress the marks upon it. Other means for applying pressure to the pipe may be employed. An instance of such means is shown in Fig. 5 in which roll 3 is carried in movable blocks 6, and these blocks are urged toward the other roll by springs 7.

It is to be understood that the apparatus illustrated and described is only one representation of various means by which the invention may be carried out.

The process constituting my invention, as will be readily understood from the foregoing description of the apparatus by which it may be carried out, consists in heating metal of the character described, extruding it from a press in tubular form and printing identifying marks upon the tube while it is warm and soft at intervals throughout its length.

I claim:

The herein-described process of marking soft metal pipe consisting in heating the metal, extruding it from a press in tubular form and printing identifying marks upon the tube while it is still warm and soft at intervals throughout its length.

GRAFTON D. DORSEY.
